AIR-COOLED ENGINE

Fritz Gosselau, Berlin-Charlottenburg, Germany,
assignor to Siemens & Halske, Aktiengesell-
schaft, Siemensstadt, near Berlin, Germany, a
corporation of Germany

Application September 26, 1933, Serial No. 690,975
In Germany September 27, 1932.

10 Claims. (Cl. 123—171)

My invention relates to an air-cooled multi-cylinder engine provided with a cooling blower.

The attempts hitherto made to increase beyond a certain measure the power of air-cooled internal combustion engines with cylinders in line have failed in that in the direction of flow of the cylinders at the rear could not be cooled to the desired extent. As a result of this defective cooling of the individual cylinders the utilization of the power of the entire engine was, therefore, limited. To overcome this drawback it has already been proposed to arrange a blower on the crank shaft, but the difficulties of an uniform cooling could not be surmounted. It has, therefore, been proposed to provide each cylinder with a blower. Such an engine, however, is heavy and complicated. The conditions of air supply to the individual blowers cannot be controlled.

The methods heretofore employed in developing an air-cooled engine with cylinders in line have not proved practical and air-cooled engines with cylinders in line over 200 H. P. did not practically come into use. Greater powers are reserved to air-cooled stationary radial cylinder aero-engines or water-cooled engines with cylinders in line. The drawbacks of the air-cooled radial cylinder aero-engine lie in its high head resistance, those of the water-cooled engine with cylinders in line in its tendency to cause a loss of the cooling water and in its heavy weight, drawbacks which an air-cooled engine with cylinders in line of considerable power would not present.

The object of my invention is to provide an air-cooled engine with cylinders in line which are actually uniformly cooled by a single blower, without impairing in any way the thermal and aero-dynamic efficiency.

The invention involves the driving of the cooling blower by the crank shaft of the motor through a transmission gear, and the supplying of the cooling air to a receiver which is so designed as to cause a substantially uniform pressure to prevail at different inlet ports leading therefrom, such inlet ports being arranged in air-guide jackets surrounding the respective cylinders and being of such form that cooling air is circulated around the individual cylinders and so distributed that the different portions of each cylinder receive different quantities corresponding with the amount of heat to which such different portions are exposed in accordance with their different distances from the lower dead centre of the piston. In this case the receiver in conjunction with the inlet ports provides for a uniform distribution of the cooling air, the form of the ports for the most economical consumption of air and the air-guide jacket for the thermally effective flow of the cooling air.

In the accompanying drawings two embodiments of my invention are illustrated in diagrammatic form.

Figs. 1 and 2 show in transverse sectional elevation and in horizontal section respectively an engine with two rows of inverted cylinders set at an angle to one another and the arrangement of a receiver at the outer side of each row of cylinders.

Fig. 3 represents a transverse sectional front elevation through a cylinder pair in Fig. 4, showing a modified form of air supply;

Fig. 4 represents a horizontal section through the cylinder Fig. 3 similar to the one shown in Fig. 2, and

Fig. 5 represents a side elevation of this modification, partly in central longitudinal section.

In Figs. 1 and 2, 1 denotes the crank case, 2 and 3 the two rows of inverted cylinders set at an angle to one another. A blower 4 driven by the engine through a transmission gear (not shown) is located in the upper part of the crank case. The blower 4 supplies air through the ducts 5 and 6 to receivers 7 and 8 located at the outer side of each row of cylinders. The crank case 15 has a compact and substantially oval cross-section. It, therefore, takes up but a small space and is resistant to deformations and to oscillations of the walls. The fuselage 32 may be easily adapted to the engine and has a suitable cross-section. The crank case is built integral with the individual air-guide jackets 9 and 10 of which one is provided for each of the cylinders 2 and 3 in the two rows and which are connected with one another to form an integral body. The crank 25 case is considerably stiffened by the air-guide jackets and protected against deflection. The air-guide jackets may, however, be also mounted on the crank case in the form of a separate block. Such an arrangement also stiffens the crank to 30 a great extent. The air-guide jackets are provided with inlet ports 11 and 12, shown partly in dotted lines in Fig. 1 for the cooling air, which parts may be arranged in the path of flow in order to present as little resistance as possible 35 to the flow of air. They are so dimensioned that a greater quantity of cooling air comes into contact with the surfaces exposed to a high temperature than with the surfaces exposed to a low temperature as seen in Fig. 1. The cross-section 40 of the inlet ports is considerably larger in the neighborhood of the cylinder head than at the lower end of the cylinder. By adapting the cross-section of the inlet openings to the different cross-sections of the ducts a greater amount of 45 cooling air may be supplied per unit of time to the hotter head of the cylinder than to the lower end thereof, where lower temperatures prevail. Exhaust ports 13 and 14 are located at the 50 opposite side of the air jackets. In this case 55

the air may escape, if desired, through diffusers into the space between the rows of cylinders.

The walls of the receivers 7 and 8 are formed partly of the crank case and partly of the air-guide jackets. In this manner the crank case is effectively cooled and at the same time heat is also abstracted from the outer surface of the air-guide jackets. The outer walls 15 and 16 of the receivers 7 and 8 are built integral with the 10 crank case and, consequently, also serve to stiffen the crank case.

The cooling air from the receivers 7 and 8 is not only directed around the cylinders but also passes along the valves, that is first along the 15 exhaust valves 19 and 20 through outlet openings placed at the lower end of the receivers as indicated at 17 and 18. The pipe connections 21 and 22 of the exhaust valves 19 and 20 are provided with cooling ribs. The cooling air on passing 20 along the exhaust valves gets hotter and may, consequently, preheat the fuel mixture flowing through the inlet pipes 23, 24.

The pipe connections 21 and 22 of the exhaust valves 19 and 20 do not form directly the valve 25 seats for these valves but the valve seat is rather surrounded by a particularly good heat conducting jacket which comes into contact with the cooling medium. By the insertion of the heat conducting part an effective cooling of the exhaust 30 valve is ensured without thereby causing other important parts to operate under unfavorable working conditions. In this manner the heat produced at any point in the neighborhood of the exhaust valve is carried off at once so that 35 no other parts, for instance the liner of the cylinder, are affected. This heat conducting part with which the exhaust valve is provided is denoted by the numeral 22'.

The inlet and exhaust ports 11, 12, 13 and 14 40 of the cylinder cooling jackets extend from the cylinder head downwardly to the lower end of the jackets, and thus impair the stiffening of the crank case to a certain degree. This is compensated by providing the cylinders 25 with flanges 45 26 which are situated at the valve ends of the liners and cover the outer ends of the cooling jackets. In this manner the structure of the air-guide jackets is further stiffened. The fastening of the cylinders is, for instance, effected by 50 bolts 27.

The arrangement of the flanges 26 in the neighborhood of the cylinder head does not only serve to increase the stiffening of the crank case with the cooling jackets, but it also compensates 55 for the deformations caused by the heat. Air-cooled cylinders whose flanges are situated in the neighborhood of the lower dead centre expand to such an extent in operation as a result of the heat that the valve clearance becomes greater, 60 since the center of rotation of the valve rocker upon the expansion of the cylinders is shifted away from the end of the push rods. Since too great a valve clearance may give rise to serious valve ruptures, high power air-cooled internal 65 combustion engines are equipped with a device for compensating the valve clearance. This, however, results in complicated, expensive and heavy constructions, whereas in an arrangement according to the invention provisions for compensating 70 the valve clearance need not be made. The cylinders expand toward the crank shaft, which has no influence upon the position of the center of rotation for the valve rocker. The cooling air jackets to which the cylinder flanges 75 are secured remain sufficiently cool so that they

do not cause a displacement of the center of rotation for the valve rocker.

In case the cooling jackets should nevertheless expand as a result of a slight amount of heat present therein to such an extent that the valve clearance might be impaired, this expansion is compensated for in the engine according to the invention by the fact that the cooling air, which gets hot upon being directed around the cylinder, strikes the push rods and heats the latter to such 10 a degree that the expansion of the cooling air jacket is effectively compensated. 5

Since the cooling air on passing through the cooling jacket takes up a considerable amount of heat its volume increases. In order to avoid a 15 throttling of the cooling air flowing around the cylinders and, consequently, an increase of power required for the blower, the cooling jackets are eccentrically arranged around the cylinder. They are in the neighborhood of the air inlet ports 11 and 12 disposed nearer the cylinder wall than they are in the neighborhood of the air exhaust ports 13 and 14. 20

Consequently, the cooling ribs 30, 31, which are adapted to the diameter of the cooling jacket, 25 are of smaller height at the air inlet ports than at the air exhaust ports, as clearly shown in Fig. 1.

Instead of supplying the cooling air through means located on the outside of the two rows of cylinders, a central receiver located between the 30 two rows may be employed. This modification is shown in Figs. 3 to 5.

In Figs. 3 to 5, 1 denotes the crank case of the internal combustion engine. 2 and 3 are the two rows of cylinders set at an angle to one another. 35 The cooling blower 4' delivers cooling air through the pipe connection 5' and the pipe 6' to the receiver 7' which is located between the two cylinder blocks. The cylinders are provided with cooling fins 8' and cooling jackets 9. The cooling 40 air flows from the receiver 7' through the ports 10' between the cooling jackets of the cylinders and through the ports 11' to outside atmosphere. By causing the air to flow into the receiver at the end opposite to the cooling blower 4' a favorable 45 position of the exhaust ports is attained, since the air may flow off in a direction opposite to the direction of flight.

In the hitherto known engines cooled by blowers the cylinders could receive different quantities of cooling air depending upon their position with respect to the cooling blower since the air on reaching the last outlet port decreases in pressure considerably. The cylinder worst cooled diminishes the power of the entire engine. As 55 compared to the previously known engines cooled by blowers the invention shows how a greater number of cylinders may be uniformly supplied with cooling air so that the output of the engine may be developed to a much greater extent. 60

I claim as my invention:

1. An air cooled internal combustion engine comprising a plurality of cylinders arranged in series, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective 75

- jackets, and a blower for delivering cooling air into said receiver.
2. An air cooled internal combustion engine comprising two rows of cylinders, those of one row set at an angle to those of the other, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver extending along one side of each row of cylinders and their jackets, bounded at least partly by those portions of the jackets in which their inlet openings are located, so as to maintain direct communication for cooling air from said receiver to the respective jackets, and a blower for delivering cooling air into said receiver.
3. An air cooled internal combustion engine comprising two rows of cylinders, those of one row set at an angle to those of the other, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver arranged between said two rows of cylinders and their jackets, bounded at least partly by those portions of the jackets in which their inlet openings are located, so as to maintain direct communication for cooling air from said receiver to the respective jackets, and a blower for delivering cooling air into said receiver.
4. An air cooled internal combustion engine comprising two rows of cylinders, those of one row set at an angle to those of the other, a crank case, a cooling air jacket enclosing each cylinder and having inlet and outlet openings for permitting cooling air to be forced around its respective cylinder, said jackets being integral with said crank case and the inlet opening of each of said jackets being in the form of a slot which decreases in width from the valve end of the cylinder toward the crank end thereof, an air receiver extending along one side of each row of cylinders and their jackets, bounded at least partly by those portions of the jackets in which their inlet openings are located, so as to maintain direct communication for cooling air from said receiver to the respective jackets, and a blower for delivering cooling air into said receiver.
5. An air cooled internal combustion engine comprising a plurality of cylinders arranged in a series, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, and a blower disposed at one end of said receiver and delivering cooling air into same at the opposite end thereof.
6. An air cooled internal combustion engine comprising a plurality of cylinders arranged in series, a crank case, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, and a blower for delivering cooling air into said receiver.
7. An air cooled internal combustion engine comprising a plurality of cylinders arranged in series, a crank case, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, and a blower for delivering cooling air into said receiver.
8. An air cooled internal combustion engine comprising a plurality of cylinders arranged in series, exhaust valves for said cylinders, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, ports for directing cooling air from said receiver around said cylinder exhaust valves, and a blower for delivering cooling air into said receiver.
9. An air cooled internal combustion engine comprising a plurality of cylinders arranged in series, exhaust valves for said cylinders, heat conductive housings around said exhaust valves, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, ports for admitting cooling air from said receiver to said heat conductive housings, and a blower for delivering cooling air into said receiver.
10. An air cooled internal combustion engine comprising a plurality of cylinders arranged in series, a cooling air jacket enclosing each cylinder and having inlet and outlet openings for permitting cooling air to be forced around its respective cylinder, the inlet opening of each of said jackets being in the form of a slot which decreases in width from the valve end of the cylinder toward the crank end thereof, an air receiver common to the series of cylinders and their jackets, bounded at least partly by those portions of the jackets in which their inlet openings are located, so as to maintain direct communication for cooling air from said receiver to the respective jackets, and a blower for delivering cooling air into said receiver.

said jackets being in the form of a slot which decreases in width from the valve end of the cylinder toward the crank end thereof, said jackets being eccentrically arranged with respect to their cylinders to provide increasing air passage space from their inlet to their outlet openings, an air receiver common to the series of cylinders

and their jackets, bounded at least partly by those portions of the jackets in which their inlet openings are located, so as to maintain direct communication for cooling air from said receiver to the respective jackets, and a blower for delivering cooling air into said receiver.

FRITZ GOSSLAU.
